No. 37,290.

Patented January 3, 1905.

UNITED STATES PATENT OFFICE.

MAX MITTENDORFF, OF NEW YORK, N. Y., ASSIGNOR TO THE SUTRO BROS. BRAID COMPANY, OF NEW YORK, N. Y., A CORPORATION OF NEW YORK.

DESIGN FOR BRAID.

SPECIFICATION forming part of Design No. 37,290, dated January 3, 1905.

Application filed November 25, 1904. Serial No. 234,296. Term of patent 3½ years.

To all whom it may concern:

Be it known that I, MAX MITTENDORFF, a citizen of the United States, residing at New York city, county and State of New York, 5 have invented a new, original, and ornamental Design for Braid, of which the following is a specification.

This invention relates to a new, original, and ornamental design for braid, and is illustrated in the annexed drawing, in which is shown a plan view of the braid.

What I claim as new, and desire to secure by Letters Patent, is—

The ornamental design for a braid substantially as herein shown.

MAX MITTENDORFF.
